THOMAS H. BURRIDGE, OF ST. LOUIS, MISSOURI, ASSIGNOR TO HIMSELF
AND G. C. FABIAN, OF THE SAME PLACE.

Letters Patent No. 64,070, dated April 23, 1867.

IMPROVEMENT IN STEAM SAFETY-VALVES.

The Schedule referred to in these Letters Patent and making part of the same.

TO ALL WHOM IT MAY CONCERN:

Be it known that I, T. H. BURRIDGE, of St. Louis, in the county of St. Louis, and State of Missouri, have invented certain new and useful improvements in Steam Safety-Valves; and I do hereby declare that the following is a full and complete description of the construction and operation of the same, reference being had to the accompanying drawings, making a part of this specification, in which the drawing is a view of the valve apparatus.

A represents a section of a steam boiler, B the seat of the safety-valve, C the valve, D the link by which the valve is attached to the lever E. F is a supplementary lever, to the free end of which is attached the weight G. H are standards, to which the levers are pivoted, and I a yoke, by the means of which the levers are kept in proper relation to each other. It will be seen that the free end of the lever E is made to curve upward, thus presenting a curving upper side to the lower side of the lever F, which is provided with a corresponding curvature, the two fitting into each other, as shown in the drawing. The position of the levers as thus shown is such as when the valve is at rest or closed. In this position the lever F rests upon the lever E at the point X, and at which point the weight exerts the least amount of resistance to the pressure of the steam upon the valve, which, by way of illustration, may be supposed to be one hundred pounds, which is as much as the boiler is allowed to carry. Now, if the pressure of the steam be raised above one hundred pounds, the valve opens, and as it opens the effective resistance of the weight increases by the shifting of the points where the two levers touch; that of the lever E nearer to the free end, and that of F nearer to the pivoted end, thus multiplying the resistance of the weight by changing the relation of the levers according to the pressure of the steam above one hundred pounds exerted on the valve. By this it will be evident that all excess of steam above one hundred pounds will be allowed to blow off, and the valve immediately closed when the extra pressure is reduced, which is not the case when the ordinary safety-valve is used, for it will allow the steam to blow off when below what the boiler may be allowed to carry, for the momentum of the steam will not permit the valve to return to its seat until the pressure of steam in the boiler has sunk very much below what the boiler is allowed to bear, and thus occasion a loss of steam. This defect arises from several causes: first, the valve presents a larger surface to the escaping steam when up and blowing off, than when down or closed, hence is required a greater pressure to lift the weight in consequence of this expansion of the steam by the opening of the valve; secondly, the lever on rising from its statical position, moves the weight through the arc of a circle, thereby shortening the length of the fulcrum, and, as a consequence, more pressure is required to raise the weight, but the principal reason is the momentum of the steam caused by the blowing off from the boiler. Liquids and fluids being governed by the same law, when at rest or confined, there is a dead pressure, more or less, according to circumstances; but when allowed to escape there is an increased pressure or power from the velocity of the escaping steam. This additional pressure is sometimes so great on the valve as to throw the weight and lever entirely from their place, and in most instances prevents the valve from returning to its seat until the pressure is very much reduced below that allowed the boiler to carry, and thus causing a large waste of steam. By the application of this arrangement of levers this difficulty is avoided, for if the steam in the boiler is raised above one hundred pounds to the inch, the lever F will be first raised, and in raising will shift the fulcrum in both levers, and thereby effecting an increased value of the weight, which extra weight will return the valve to its seat at one hundred pounds by following down the steam as it sinks lower; that is, it will not allow the velocity of the steam to create a momentum above the static pressure in the boiler of any considerable amount when the valve has returned nearly to its seat.

Thus it will be seen that I increase the value of the weight on the safety-valve in greater proportion than the momentum increases when the steam lifts the valve. This compensating power of the levers meets and resists the increased pressure on the valve occasioned by the momentum of the steam, for suppose the ordinary safety-valve to be raised out of its normal position by an excess of steam, then if a little extra weight is added to the lever the valve will return to its statical position long before it would if allowed to return without this additional weight being applied. The result will be no loss of steam below what the boiler is allowed to carry; but without this additional weight the valve will continue up by the momentum, and the steam escape until the

pressure sinks very much below what the boiler will bear, and thus occasion a loss of steam. This additional weight is what this compensating lever will supply, and thereby prevent a loss of steam in blowing off as above said.

What I claim as my improvement, and desire to secure by Letters Patent, is—

The levers E F, constructed and arranged in relation to each other, and valve, substantially as and for the purpose set forth.

THOMAS H. BURRIDGE.
